OPERATING MEANS FOR WINDOW REGULATOR MECHANISM

James D. Leslie and Louis P. Garvey, Birmingham, and
Wilson H. West, Madison Heights, Mich., assignors to
General Motors Corporation, Detroit, Mich., a corpora-
tion of Delaware

Application August 6, 1958, Serial No. 753,535

14 Claims. (Cl. 268—126)

This invention relates to operating means for window regulator mechanisms and more particularly to operating means for vehicle window regulator mechanisms.

The operating means of this invention is of the type which is selectively operable from the exterior of the vehicle to move a vehicle window between open and closed positions and which may also be selectively and alternately placed in locked inoperative or unlocked inoperative conditions. Such an operating means is particularly useful for station wagon tail gate windows wherein it is desirable that an exterior operating means be provided to selectively move the window between open and closed positions and that this operating means be able to be placed in a locked inoperative condition to prevent unauthorized entry into the vehicle.

Generally, the operating means includes an operating member rotatably mounted on the body, a manually operable handle swingably mounted on the member for movement between an open operating and a closed non-operating position with respect to a handle receiving housing therein which opens to a handle receiving recess on the body, each of which receive portions of the handle in the closed position thereof. The operating member supports a key cylinder assembly movable between locked and unlocked positions with respect thereto and controlling operations of a clutch means to selectively and alternately clutch and declutch the operating member from the window regulator mechanism. When the key cylinder assembly is locked to the operating member, the operating member is declutched from the window regulator mechanism whereby even if the handle is moved to an open position and the operating member rotated, the window will remain in closed position. When the key cylinder assembly is unlocked from the operating member it is manually movable to first and second positions with respect thereto, the first position acting to clutch the operating member to the window regulator mechanism whereby rotation of the handle moves the window between open and closed positions, and the second position acting to declutch the operating member from the window regulator mechanism in order that the handle receiving recess of the operating member may be aligned with the handle receiving recess on the body so that the handle may be moved to a closed position. Thus, when the key cylinder assembly is in an unlocked position, the operator may move the window to any position at his will. However, if the key cylinder assembly is in locked position, the window cannot be moved.

The primary object of this invention is to provide an improved operating means for vehicle window regulator mechanisms. Another object of this invention is to provide an improved operating means for vehicle window regulator mechanisms wherein the operating means is selectively operable from the exterior of the body to move the window between open and closed positions and may also be placed in a locked inoperative position to prevent unauthorized entry into the body. A further object of this invention is to provide an improved manual

2

operating means for vehicle window regulator mechanisms which includes a manually operable handle movable between open and closed positions with respect to a rotatable operating member and latch controlled clutch means for selectively and alternately clutching and de-clutching the operating member from the window regulator mechanism.

These and other objects of this invention will be readily apparent from the following specification and drawings, wherein:

Figure 1 is a partial rear elevational view of a station wagon body embodying an operating means according to this invention;

Figure 2 is an enlarged partially broken away elevational view of the operating means, with the manually

operable handle being shown in open position; Figure 3 is an enlarged sectional view taken along the plane indicated generally by line 3—3 of Figure 1, with the manually operable handle being shown in closed position;

Figure 4 is an enlarged sectional view taken along the plane indicated generally by line 4-4 of Figure 3;

Figure 5 is an enlarged sectional view taken along the plane indicated generally by line 5-5 of Figure 3; and,

Figure 6 is an enlarged sectional view taken along the plane indicated generally by line 6-6 of Figure 3.

Referring now particularly to Figure 1 of the drawings, a station wagon body 10 includes a tail gate 12 which is swingably mounted on the body at its lower edge 14 for movement between a closed position, as shown, and an open position wherein the tail gate is disposed in a generally horizontal position. The tail gate 12 supports a window 16 which is movable between a closed position, as shown, and an open position within the tail gate, not shown. When the window 16 is in closed position, the upper and side edge portions thereof are received within a guide channel 18 of the body. Thus, the window 16 must be in an open position within the tail gate before the tail gate can be opened.

The window 16 is moved between open and closed positions by a window regulator mechanism which generally includes a pair of lift arms 20 and 22 pivotally

5 mounted on the tail gate 12 at 24 and mounting rollers 26 which are pivotally and slidably received in cam channels 28 fixed to the lower edge of the window. The lift arms include intermeshing sector gears 30, with the sector gear of lift arm 22 being driven by a pinion 32.

It is desirable that the window regulator mechanism be operable from the exterior of the body by an operating means and that this operating means be able to be locked or placed in an operative condition to prevent unauthorized entry into the body. 10 This invention

provides such a window regulator operating means 34 which may be operated from the exterior of the body and which includes means for selectively and alternately placing the operating means in operative or inoperative conditions. This operating means will now be described with reference to Figures 2 through 6 of the drawings.

As best shown in Figure 3 of the drawings, a circularly shaped housing 40 fits flush within a localized embossment in the tailgate outer panel 42 and includes a central hub portion 44 which fits within an opening 46 of panel

42. Housing 40 is bolted at 43 to panel 42. A handle assembly 48 is rotatably supported by housing 40 and includes a generally circularly shaped handled support

or operating member 50 and a manually operable handle 52 swingably secured thereto. The handle support 50 seats against the outer end of hub 44 and includes a central hub 53 rotatably received within hub 44 and fixed against axial outward movement thereof by means of a

split ring 54 which is received within a groove 56 of hub 53 and bears against a washer 58 located between the split ring and the inner end of hub 44. Bearing shoes 59 are further provided on support 50 to bear against housing 40 and thereby stabilize the support 50 against tilting movement. The handle 52 includes a mounting lug 60 at one end thereof received within a radial groove 62 of support 50. A pin 64 extends through lug 60 and the ends of the pin are received within opposite slots 66 provided in support 50 which open to the inner side thereof and also to groove 62. The ends of the pin 64 are held against the outer ends of the slots 66 by means of angle brackets 68 having one leg thereof bolted at 70 to the rear wall of support 50 and the other leg thereof bearing against the ends of the pin to hold these ends in engagement with the outer ends of the slots. The body of handle 52 is of generally circular shape so as to be received within a similar shaped recess 71 in support 50 in the closed position thereof. An operating knob 72 is rotatably mounted on a lug 74 at the other end of the handle by means of a bolt 75 which is recessed into the knob 72. When the handle 52 is in closed position, as shown in Figure 3, the knob 72 extends through a generally rectangularly shaped opening 76 of support 50 into a similarly shaped recess 78 of housing 40 which extends inwardly within the opening 46 of panel 42. The handle 52 is secured in place in closed position by a generally U-shaped spring 80 riveted at 82 to the base of recess 78 and having reversely bent legs 84, Figure 2, which engage behind a rib 86 of knob 72.

A lock cylinder housing 88 is received within the hub 53 of support 50 and is keyed to the support for rotation therewith by means of an axial rib 90 of housing 88 being received within an axial groove 92 in hub 53. A lock cylinder 94, Figures 3 and 5, is received within housing 88 and is of conventional side locking bar type having a side locking bar 96 which is spring biased inwardly of the lock cylinder so as to be retracted therein when the inner beveled edge of the bar is aligned with the tumbler notches 97, upon insertion of a suitable key 98 within the key slot 99 to move the tumblers 100 to a non-blocking position. As can be seen in Figure 5 of the drawings, the locking bar 96 is adapted to fit within either of a pair of longitudinal slots 101 and 102 provided in housing 88, with slot 101 being of circumferential width substantially equal to the width of the side locking bar to prevent rotational movement of the lock cylinder relative to housing 88 when the bar is within this slot, while slot 102 is of a substantial circumferential width as compared to the width of the side locking bar so that the lock cylinder 94 may be rotated through a substantial arc relative to housing 88 when the locking bar is within this slot. The lock cylinder 94 is keyed to the housing 88 for rotation relative thereto by means of a pin 103 which fits within grooves provided in the lock cylinder housing 88 and the lock cylinder 94. Thus the lock cylinder is held against movement outwardly of the housing 88.

The lock cylinder 94 includes a lug 104 which is eccentrically located with respect to the axis of rotation thereof and is received within a slot 106 of locking pawl 108. Pawl 108 is slidably mounted within a bore 110 of housing 88, the opening of which is adapted to be aligned with a slot 112 provided in the hub 53 of support 50. The pawl is continually urged outward of bore 110 by means of a coil compression spring 114 which is received within a bore 116 of the pawl and seats on a lug 118 of housing 88.

A driving hub 120 is rotatably mounted on the inner end of hub 53 and is rotatably secured thereto by means of a split ring 122 which is received within a groove provided in an axial lug 124 of housing 88 which projects through the base of hub 120. A washer 126 is provided between the split ring and the base of hub 120. The hub 120 further includes an axial slot 128 which is

adapted to be aligned with bore 110 and slot 112, and a pair of diametrically opposite axial slots 130 which slidably receive a shaft 132. Shaft 132 is rotatably mounted at 134 between the legs 136 of a yoke 138. Yoke 138 is secured to a shaft 140 which also includes the pinion gear 32 meshing with the sector gear 30 of arm 22, as previously described in conjunction with Figure 1 of the drawings.

A manually operable handle 142, Figures 2 and 6, is secured to the lock cylinder 94 in a suitable manner, such as by staking. A leaf spring 144 is received within the recess 145 therein. The leaf spring 144 is welded at 147 to handle 142 and includes a V-shaped detent portion 146 which is adapted to fit within any one of three V-shaped notches 148, 150 and 152 provided in a circumferential flange 154 of housing 88. As can be seen from Figure 2 of the drawings, the handle 142 includes a pointer and operating knob 156 which is movable relative to the support 50 with respect to the words "lock," "fold" and "open" marked thereon, with the "lock" position of handle 142 corresponding to engagement of detent 146 with notch 148, the "fold" position of handle 142 corresponding to the engagement of detent 146 with notch 150, and the "open" position of handle 142 corresponding to the engagement of detent 146 with notch 152.

The operating means of this invention is shown in the drawings with the handle 142 in "lock" position wherein the detent 146 of spring 144 engages notch 148; with the lock cylinder 94 in a locked position with respect to housing 88 wherein the side bar 96 engages within slot 101 of housing 88; and with the lug 104 of the lock cylinder 94 engaging the lower wall of slot 106 to hold pawl 108 within slot 110 and out of slots 112 and 128. Assuming now that an unauthorized person inserts his fingers within the finger grip opening 158 of handle 52 and then moves the handle to an open operating position as shown in full lines in Figure 2 and dot-dash lines in Figure 3. If the person now turns the handle 52 to rotate the support 50, the lock cylinder housing 88 and the lock cylinder 94 will turn with the support 50 independently of hub 120, since the pawl 108 does not engage in slot 128. Thus the unauthorized person can turn the handle 52 at will, but the window 16 remains in a closed position, as shown in Figure 1, since there is no driving connection between the pawl 108 and the slot 128 of hub 120.

Assuming now that an authorized person inserts the suitable key 98 within the key slot 99 to move the tumblers 100 to a non-blocking position and allow the locking bar 96 to be spring biased inwardly of the lock cylinder 94 into engagement with the tumbler notches 97 and out of engagement with the slot 101. Thereafter, handle 142 is manually turned so that detent 146 engages notch 152, or the key is turned to so move the handle through its "fold" position to its open position. This will rotate the lock cylinder 94 in a clockwise direction, as viewed in Figure 4, so that the lug 104 of the lock cylinder will move to its position 104" to allow spring 114 to move pawl 108 outwardly of slot 110 to its position 108" within slots 112 and 128. The key 98 can now be removed so that the tumblers 100 will move the locking bar 96 outwardly of the lock cylinder 94 and into the slot 102. If the handle 52 is now turned to rotate the support 50 and the lock cylinder housing 88, the engagement of the detent 146 of spring 144 with notch 152 of housing 88 will cause the lock cylinder 94 to also rotate with housing 88. Since the pawl 108 now fits within slots 112 and 128, turning of handle 52 will cause the hub 120 to rotate with support 50 and the engagement of the slots 130 of the hub with the pin 132 will rotate the shaft 140 and the pinion 32 to thereby swing the lift arms 20 and 22 outwardly of each other and move the window 16 to an open position within the tailgate 12.

If it is thereafter desired to move the window 16 to a closed position or any other open position, the handle

52 is turned in the opposite direction to rotate the hub 120 in the opposite direction and swing the lift arms inwardly of each other.

It will be remembered that the knob 72 is received within the recess 78 of housing 40 when the handle 52 is in closed position, and that the housing 40 is fixed to the body. Since the window may be moved to various positions, the opening 76 may not be aligned with the recess 78 when it is desired to move the handle 52 to a closed position. When this occurs, the operator grasps the handle 142 and moves the handle to its "fold" position, thereby moving the detent 146 of spring 144 out of engagement with notch 152 and into engagement with notch 150 and also rotating the lock cylinder 94 relative to housing 88, as side bar 96 moves within slot 102, to a position wherein the lug 104 is in position 104', Figure 4, to move pawl 108 to its position 108' out of engagement with slots 112 and 128. Since the pawl 108 is no longer in engagement with slot 128, the support 50, the lock cylinder housing 88 and the lock cylinder 94 can again be rotated independently of the hub 120 by handle 52 until the opening 76 is aligned with the recess 78 so that the handle 52 can then be moved to a closed position, as shown in Figure 1, wherein the knob 72 is received within the recess 78 in engagement with the legs 84 of spring 82.

If the operator thereafter desires to move the window to some other position, he merely moves the handle 52 to its open operating position, as shown in Figure 2; moves the handle 142 from "fold" to "open" position to rotate the lock cylinder 94 relative to housing 88 and move the lug 104 to its position 104" and allow pawl 108 to move to its position 108" in engagement with slots 112 and 128; and then turns the handle 52.

Assume now that the window 16 has been moved to the desired position, the opening 76 is aligned with recess 78, and that the operator desires to place the operating means in a locked or inoperative position. The operator inserts the key 98 within the key slot 99 to retract the side bar 96, as previously described, out of slot 102 and thereafter moves the handle 142 from either "fold" or "open" position to "lock" position. This will move the side bar 96 into alignment with slot 101 of housing 88, and if the key is thereafter retracted, the tumblers 100 move the side bar 96 into engagement with the slot 101. Thus the operating means is now in a locked or inoperative position and the handle 52 is then moved to a closed position.

Thus this invention provides a new and improved operating means for a vehicle window regulator mechanism which is selectively operable from the exterior of the vehicle to move a vehicle window between open and closed positions and which may be selectively and alternately placed in a locked inoperative condition wherein the operating means will not operate the window regulator mechanism to thereby prevent unauthorized entry into the vehicle.

What is claimed is:

1. In a vehicle body having a window mounted thereon for movement to open and closed positions and a window regulator mechanism for so moving said window, operating means for said mechanism comprising, an operating member movably mounted on said body, clutch means selectively and alternately movable to clutched and first and second declutched positions to selectively and alternately connect said operating member to said window regulator mechanism to thereby operate said mechanism or disconnect said member from said mechanism and allow said member to be moved independently thereof, and selectively operable means for locking said clutch means in one of said declutched positions to maintain said member and mechanism in disconnected relationship.

2. In a vehicle body having a window mounted thereon for movement to open and closed positions and a window regulator mechanism for so moving said window, operat-

ing means for said mechanism comprising, an operating member movably mounted on said body, clutch means selectively and alternately movable to clutched and first and second declutched positions to selectively and alternately connect said operating member to said window regulator mechanism to thereby operate said mechanism upon movement of said operating member or disconnect said operating member from said window regulator mechanism and allow said operating member to be moved independently thereof, clutch operating means operable to selectively move said clutch means to said positions and means for selectively blocking operation of said clutch operating means when said clutch means is in one of said declutched positions.

3. In a vehicle body having a window mounted thereon for movement to open and closed positions and a window regulator mechanism for so moving said window, operating means for said mechanism comprising, an operating member movably mounted on said body, clutch means selectively and alternately movable to clutched or first and second declutched positions to selectively and alternately connect said operating member to said window regulator mechanism to thereby operate said mechanism upon movement of said member or disconnect said operating member from said window regulator mechanism and allow said operating member to be moved independently thereof, clutch operating means for selectively moving said clutch means to said positions, means mounting said clutch operating means on said operating member for movement therewith and movement independently thereof, and means for locating said clutch operating means with respect to said operating member to thereby locate said clutch means in said clutched and declutched positions.

4. In a vehicle body having a window mounted thereon for movement to open and closed positions and a window regulator mechanism for so moving said window, operating means for said mechanism comprising, an operating member movably mounted on said body, clutch means selectively and alternately movable to clutch or first and second declutched positions to selectively and alternately connect said operating member to said window regulator mechanism to thereby operate said mechanism upon movement of said member or disconnect said member from said mechanism and allow said operating member to be moved independently thereof, clutch operating means for selectively moving said clutch means to said positions, means mounting said clutch operating means on said operating member for movement therewith or movement independently thereof, means for selectively locating said clutch operating means with respect to said member to thereby selectively locate said clutch means in said clutched and first declutched positions, and means for selectively locking said clutch operating means to said operating member when said clutch means is in said second declutched position.

5. In a vehicle body having a window mounted thereon for movement to open and closed positions and a window regulator mechanism for so moving said window, operating means for said mechanism comprising, an operating member movably mounted on said body, clutch means selectively and alternately movable to clutched or first and second declutched positions to selectively and alternately connect said operating member to said window regulator mechanism to thereby operate said mechanism upon movement of said operating member or disconnect said member from said mechanism and allow said operating member to be moved independently thereof, clutch operating means for selectively moving said clutch means to said positions, means mounting said clutch operating means on said operating member for movement therewith or movement independently thereof, manually operable means for selectively locating said clutch operating means with respect to said member to thereby locate said clutch means in said clutched and first declutched posi-

tions, and key means for selectively locking said clutch operating means to said operating member when said clutch means is in said second declutched position.

6. In a vehicle body having a window mounted thereon for movement to open and closed positions and a window regulator mechanism for so moving said window, operating means for said mechanism comprising, an operating member movably mounted on said body, clutch means selectively and alternately movable to clutched or first and second declutched positions to selectively and alternately connect said operating member to said window regulator mechanism to thereby operate said mechanism upon movement of said operating member or disconnect said member from said mechanism and allow said operating member to be moved independently thereof, clutch operating means for selectively moving said clutch means to said positions, means mounting said clutch operating means on said operating member for movement between locked and first and second unlocked positions with respect thereto, means for selectively moving said clutch operating means between said first and second unlocked positions with respect to said member to thereby respectively move said clutch means between said clutched and first declutched positions, and means for selectively moving said clutch operating means from either of said unlocked positions to said locked position to move said clutch means between said clutched or first declutched positions and said second declutched position.

7. In a vehicle body having a window mounted thereon for movement to open and closed positions and a window regulator mechanism for so moving said window, operating means for said mechanism comprising, an operating member movably mounted on said body, clutch means selectively and alternately movable to clutched or first and second declutched positions to selectively and alternately connect said operating member to said window regulator mechanism to thereby operate said mechanism upon movement of said operating member or disconnect said member from said mechanism and allow said operating member to be moved independently thereof, key cylinder means for selectively moving said clutch means to said positions, means mounting said key cylinder means on said operating member for movement between locked and first and second unlocked positions with respect thereto, means for selectively moving said key cylinder means between said first and second unlocked positions with respect to said member to thereby respectively move said clutch means between said clutched and first declutched positions, and key means for selectively moving said key cylinder means between any of said positions thereof with respect to said operating member to move said clutch means between any of said positions thereof.

8. In a vehicle body having a window mounted thereon for movement to open and closed positions and a window regulator mechanism for so moving said window, operating means for said mechanism comprising, an operating member movably mounted on said body, clutch means selectively and alternately movable to clutched or first and second declutched positions to selectively and alternately connect said operating member to said window regulator mechanism to thereby operate said mechanism upon movement of said operating member or disconnect said member from said mechanism and allow said operating member to be moved independently thereof, key cylinder means for selectively moving said clutch means to said positions, means mounting said key cylinder on said operating member for movement between locked and first and second unlocked positions with respect thereto, and key means for selectively moving said key cylinder means between locked and one of said unlocked positions with respect to said operating member to respectively move said clutch means between one of said declutched and clutched positions.

9. In a vehicle body having a window mounted there-

on for movement to open and closed positions and a window regulator mechanism for so moving said window, operating means for said mechanism comprising, an operating member movably mounted on said body, clutch means selectively and alternately movable to clutched or first and second declutched positions to selectively and alternately connect said operating member to said window regulator mechanism to thereby operate said mechanism upon movement of said operating member or disconnect said member from said mechanism and allow said operating member to be moved independently thereof, key cylinder means for selectively moving said clutch means to said positions, means mounting said key cylinder means on said operating member for movement between locked and first and second unlocked positions with respect thereto, means for selectively moving said key cylinder means between said first and second unlocked positions with respect to said member to thereby respectively move said clutch means between said clutched and first declutched positions, and key means for selectively moving said key cylinder means between locked and either of said unlocked positions with respect to said operating member to move said clutch means between said second declutched position and either said clutched or first declutched positions.

10. In a vehicle body having a window mounted thereon for movement to open and closed positions and a window regulator mechanism for so moving said window, operating means for said mechanism comprising, an operating member movably mounted on said body, an operating handle mounted on said member for movement between open and closed positions with respect thereto, a handle receiving housing on said member for receiving a portion of said handle in the closed position thereof, said housing being provided with an opening therein, a handle receiving recess on said body adapted to be aligned with said opening to receive another portion of said handle in the closed position thereof, clutch means for selectively clutching said operating member to said window regulator mechanism to operate said mechanism upon movement of said member by said handle in the open position thereof, and first and second selectively operable means for selectively declutching said operating member from said window regulator mechanism to allow said operating member to be moved independently thereof to a position wherein said opening in said housing is aligned with said recess on said body to allow said handle to be moved to a closed position within said housing and said recess.

11. In a vehicle body having a window mounted thereon for movement to open and closed positions and a window regulator mechanism for so moving said window, operating means for said mechanism comprising, an operating member movably mounted on said body, an operating handle mounted on said member for movement between open and closed positions with respect thereto, a handle receiving housing on said member for receiving a portion of said handle in the closed position thereof, said housing being provided with an opening therethrough, a handle receiving recess on said body adapted to be aligned with said opening in said housing to receive another portion of said handle in the closed position thereof, clutch means selectively movable between clutched and first and second declutched positions to selectively clutch said operating member to said window regulator mechanism to operate said mechanism upon movement of said member by said handle in the open position thereof or to allow said operating member to be moved independently thereof to a position wherein said opening in said housing is aligned with said recess on said body to allow said handle to be moved to a closed position within said housing and said recess, means for selectively moving said clutch means between said clutched and one of said declutched positions, and means for selectively locking said clutch means in the other of said declutched positions.

12. In a vehicle body having a window mounted

thereon for movement to open and closed positions and a window regulator mechanism for so moving said window, operating means for said mechanism comprising, an operating member movably mounted on said body, an operating handle mounted on said member for movement between open and closed positions with respect thereto, a handle receiving housing on said member for receiving a portion of said handle in the closed position thereof, said housing being provided with an opening therethrough, a handle receiving recess on said body adapted to be aligned with said opening in said housing to receive another portion of said handle in the closed position thereof, clutch means selectively movable between clutched and first or second declutched positions to selectively clutch said operating member to said window regulator mechanism to operate said mechanism upon movement of said member by said handle in the open position thereof or to allow said operating member to be moved independently thereof to a position wherein said opening in said housing is aligned with said recess on said body to allow said handle to be moved to a closed position within said housing and said recess, means for selectively moving said clutch means between said positions, and means for selectively locking said clutch means in one of said declutched positions.

13. In a vehicle body having a window mounted thereon for movement to open and closed positions and a window regulator mechanism for so moving said window, operating means for said mechanism comprising, an operating member movably mounted on said body, an operating handle mounted on said member for movement between open and closed positions with respect thereto, a handle receiving housing on said member for receiving a portion of said handle in the closed position thereof, said housing being provided with an opening therethrough, a handle receiving recess on said body adapted to be aligned with said opening in said housing to receive another portion of said handle in the closed position thereof, a pawl mounted on said member for move-

ment between extended and first or second retracted positions with respect thereto to selectively connect said operating member to said window regulator mechanism to operate said mechanism upon movement of said member by said handle in the open position thereof or to disconnect said member from said mechanism and allow said operating member to be moved independently thereof to a position wherein said opening in said housing is aligned with said recess on said body to allow said handle to be moved to a closed position within said housing and said recess, means for selectively moving said pawl between said positions, and means for selectively locking said pawl in one of said retracted positions.

14. In a vehicle body having a window mounted thereon for movement to open and closed positions and a window regulator mechanism for so moving said window, operating means for said mechanism comprising, an operating member movably mounted on said body, clutch means selectively and alternately movable to clutched and first and second declutched positions to selectively and alternately connect said operating member to said window regulator mechanism to thereby operate said mechanism or disconnect said member from said mechanism and allow said member to be moved independently thereof, first clutch operating means operable to move said clutch means between clutched and one of said declutched positions, and second clutch operating means operable to move said clutch means between any of said positions.
